UNITED STATES PATENT OFFICE.

DAVID M. WILLIAMS, OF EDWARDSDALE, PENNSYLVANIA.

CHAIN-LINK.

SPECIFICATION forming part of Letters Patent No. 482,665, dated September 13, 1892.

Application filed May 11, 1892. Serial No. 432,642. (No model.)

To all whom it may concern:

Be it known that I, DAVID M. WILLIAMS, a citizen of the United States, residing at Ed-
wardsdale, in the county of Luzerne and State
of Pennsylvania, have invented certain new
and useful Improvements in Chains; and I do
hereby declare the following to be a full, clear,
and exact description of the invention, such
as will enable others skilled in the art to
10 which it appertains to make and use the same.

My invention has relation to improvements
in chain-links having a swiveled hook; and it
consists in the construction and arrangement
of parts, as will be hereinafter described, and
15 particularly pointed out in the claim.

In the accompanying drawings, Figure 1 is a
perspective view of the link, together with
a hook which is swiveled therein. Fig. 2 is a
20 perspective view of one of the sections com-
posing the link, and Fig. 3 is a perspective
view of the hook employed in connection with
the link.

Referring by letter to the said drawings, A' indicates the link, which comprises the sections B'. These sections B', which are simi-
25 lar in form and construction, respectively
comprise the body a², of a general loop form,
having the opening a³ and a flat inner side,
the transverse apertures b', formed in the
30 body adjacent to the opening a³, the shoulder
c', extending from the inner side of the body,
preferably at a point opposite to the opening
a³, the studs d', extending from the inner side
35 of the body on opposite sides of the shoulder
c' and adapted to take through the apertures
b' of the other section and be riveted to con-
nect the sections together, and the extended
portion e, having a groove f, of semicircular

form in cross-section in its inner side, and a
seat g at the inner end of said groove.

Journaled in the bearing formed by the
grooves f in the extended portions of the sec-
tions B', forming the link A', is the shank C
of the hook D, which shank is reduced, as
shown, so as to form the shoulder h and the 45
head i, which latter rests in the seat g of the
said link A' and prevents a casual discon-
nection of the hook from the link.

Having thus described my invention, what
I claim, and desire to secure by Letters Pat- 50
ent, is—

In a chain substantially as described, the
combination, with a link consisting of two sec-
tions respectively comprising the body of a
general loop form having an opening, the 55
transverse apertures formed in the body ad-
jacent to the opening therein, the shoulder
extending from the inner side of the body, the
studs extending from the inner side of the
body on opposite sides of the shoulder and 60
adapted to take through the transverse aper-
tures of the other section and be riveted, and
the extended portion e, having a groove f, of
semicircular form in cross-section, in its in-
ner side, and the seat g at the inner end of 65
said groove, of the hook having its shank
journaled in the bearing formed by the grooves
f of the extended portion e and reduced to
form the shoulder h and the head i, substan-
tially as specified.

In testimony whereof I affix my signature in
presence of two witnesses.

DAVID M. WILLIAMS.

Witnesses:

GEORGE LEWIS,
NEIL McKECHNIE.
